UNITED STATES PATENT OFFICE.

ARLO W. SWANSON, OF ALCESTER, SOUTH DAKOTA.

SNOW-HANDLING MACHINE.

Application filed October 1, 1924. Serial No. 741,014.

My invention relates to snow handling machines and particularly to a machine of this kind adapted among other things for cleaning snow from streets and highways.

5 The object of my invention is to provide a machine of the kind mentioned of comparatively simple, durable and inexpensive and very effective construction.

One purpose of my invention is to provide 10 such a machine, which forms in itself a unit that can be connected with the front of a truck or tractor, which furnishes the means for advancing the machine over the ground, the machine, however, being provided with 15 power for operating its own mechanism.

Another object is to provide in such a machine a conveyor and suitable means for breaking up and feeding snow to the conveyor.

20 Another purpose is to provide in such a machine a conveyor combined with a second conveyor with means for regulating the feeding of the snow to the second conveyor.

Still a further object is to provide in such 25 a machine a blower or blowers for discharging the snow at the side of the pathway being cleaned.

In addition, it is my purpose to provide in 30 a machine of the kind under consideration a number of adjustments and refinements in constructions hereinafter more fully explained, which contribute to the effective operation of the device.

With these and other objects in view, my 35 invention consists in the construction, arrangement and combination of the various parts of my snow handling machine, whereby the objects contemplated are attained, as hereinafter more fully set forth, pointed out in 40 my claims, and illustrated in the accompanying drawings, in which:—

Figure 1 shows a top or plan view of a snow handling machine embodying my invention, parts of the blower pipe being broken 45 away.

Figure 2 shows a longitudinal, vertical, sectional view taken on the line 2—2 of Figure 1.

Figure 3 shows a similar view taken on the line 3—3 of Figure 1.

50 Figure 4 is a sectional view taken on the line 4—4 of Figure 1.

Figure 5 is a detail, sectional view taken on the line 5—5 of Figure 4, illustrating some of the operating mechanism.

Figure 6 is a detail, sectional view taken 55 on the line 6—6 of Figure 5.

Figure 7 is a detail, sectional view taken on the line 7—7 of Figure 4, illustrating the cam structure.

Figure 8 is a side elevation of the adjustable hood at the end of the blower pipe; and

Figure 9 is a detail, sectional view taken on the line 9—9 of Figure 1.

My improved snow handling machine has 60 its own supporting frame, so that it can be 65 built as a unit and then suitably connected with the front of a truck, tractor or the like.

The frame is shown in Figures 1 and 2 and comprises the spaced side members 10 arranged longitudinally of the machine.

70 It will be understood that the parts of my machine may be made of the material, shapes and sizes desirable for the purpose.

For the purposes of illustration, I have 75 shown the frame members 10 made of T-iron. Near their rear ends, the frame members 10 are connected by two cross frame members 11 spaced from each other lengthwise of the machine.

Near their forward ends, the frame members 10 are connected by a transverse frame member 12, as shown in Figure 2 and also in Figure 4.

80 Mounted on the frame members 11 at the rear part of the main frame of my snow-handling machine is a power plant, such for instance as the internal combustion engine 13, which supplies the power for operating the mechanism of the machine.

The forward end of the frame is supported 85 on a pair of laterally spaced castor wheels 14 supported on and below the transverse frame member 12.

The forward ends of the frame member 10 carry a transverse shaft 15. The operating 95 mechanism of my machine is pivotally supported on the shaft 15.

The operative mechanism includes a pair of upright side members 16 through the lower portions of which the shaft 15 extends. At 100 the forward end of each member 16 is fixed a disc 17 having a peripheral inwardly extend-

ing flange 18, as shown in Figure 4, and having on its inner face a cam groove 19. (See Figure 7.)

A transverse shaft 20, illustrated in Figures 2 and 4, is rotatably mounted in the discs 17. Fixed on the shaft 20 adjacent to the respective discs 17 are discs 21.

Slidably mounted in the disc members 21 are four spaced parallel shafts 22 on the ends 10 of which are rollers 23 which travel in the cam grooves 19. (See Figures 2, 4 and 7.)

Pivoted on each shaft 22 is a snow pusher blade 24 extending substantially from one disc 21 to the other and preferably curved 15 from side edge to side edge as illustrated for instance in Figure 2.

The discs 21 are provided with arcuate slots 25 in which the shafts or rods 22 may travel.

At their edges opposite the shafts 22, the 20 pusher blades 24 are pivotally mounted on cross rods 26, having their ends fixed to the discs 21 near the peripheries thereof as illustrated in Figure 2.

It will be seen that as the discs 21 rotate, 25 the pusher blades 24 will reciprocate inwardly and outwardly according to the travel of the rollers 23 in the cam slot 19.

Adjacent to each slot 25, a shield 27 is secured at its ends to the discs 21 and extends 30 between said discs. These shields are arranged so that as the swinging edges of the pusher blades 24 move inwardly, the shields will prevent inward movement of snow past the swinging ends of the pusher blades.

35 The means for rotating the shaft 20 carrying with it the discs 21 and rods 26 will be hereinafter more fully referred to.

It will be noted, however, that as the discs 21 rotate in the direction indicated by the 40 arrow A in Figure 2, the cam slot is so shaped that the discs form pockets for picking up the snow at the lower forward portion of the device, which snow is discharged at the rear upward portion of the rotary device as the 45 pusher blades move outwardly.

There is provided a cover plate and pusher blade cleaner 29 at the lower rear part of the rotary device heretofore described, which is supported on the wall members 16 and extends 50 from a point at the rear of the rotating device below the middle thereof downwardly and forwardly to position forwardly of the vertical center through the rotating device.

The shield 29 is provided at its lower part 55 with a series of shoes or runners 31 on which the device may slide on the pavement or ground.

The snow is discharged from the rotary device already described upon an endless carrier later herein referred to.

It may be said, however, before leaving the rotary device that the cam slot 19 is so arranged that the pockets are open to their deepest depth when the respective shields 60 27 clear the forward end of the shield 29 and

the pusher blades 24 begin to move outwardly for discharging their load, as the snow passes over the top of the rotating device.

The pusher members 24 are at the outward limit of their movement when the rollers move 70 from the point B of the cam slot until they reach the point C and as a result, each pusher blade 24 is scraped clean by the scraper or cleaner portion 30 at the upper rear edge of the shield 29. 75

As the rollers move from the point C to the point D, the pusher blades move inwardly for opening the pockets to their greatest depth, and the pockets remain open until the rollers reach approximately the point E. 80

The snow is discharged from the rotary snow receiving and carrying device heretofore described an endless carrier.

Spaced from the rear lower part of said rotary device, a transverse shaft 32 is mounted 85 between the end members 16 and rearwardly and upwardly therefrom another transverse shaft 33 is mounted between the side frame members 16.

On the shafts 32 and 33 are sprockets 34 90 and 35 on which travel chains 36, close to the side members 16.

A substantially rigid shield and bottom member 37 covers the shafts 32 and 33 and extends between them below the upper stretches 95 of the chains 36 and between the side members 16. Cross bars 38 are secured to the chains 36 for carrying the snow rearwardly and upwardly along the bottom member 37 for discharge into the second conveyor hereinafter referred to.

Below the lower stretches of the chains 36, a shield 39 extends between the side members 16. Just rearwardly and below the discharge end of the conveyor just described, a transverse shaft 40 is mounted in the side walls 16. The shaft 40 is in a channel-shaped conveyor casing 41, shown for instance in Figure 4.

The rear wall of the conveyor casing 41 extends upwardly and over said casing as illustrated at 43 in Figure 2 to a line substantially above and slightly rearwardly from the shaft 33.

Midway between the ends of the conveyor casing 41, the casing is formed with an inwardly extending, rearwardly opening channel 44 in its lower portion, which practically divides the casing into two compartments.

On the shaft 40 on opposite sides of the channel portion 44 are blades or arms 45, which are so arranged on the opposite sides of said channel portion as to convey the snow discharged into said compartments respectively to the left and to the right.

At each end of the conveyor casing 41 is a fan casing 46 arranged just inside the walls 16. Within the fan casing 46, fan blades 47, shown in Figure 4 and in dotted lines in Figure 2, are mounted.

The fan blades 47 are fixed to the shaft 40. 130

Each fan casing 46 is open as at 48 on its side adjacent to the conveyor casing 41.

At the top of each fan casing at the rear portion thereof is a discharge pipe 49 on which is pivotally mounted a longer discharge pipe 50, having at its outer end an adjustable hood 51 of known construction. The hood 51 is adjusted by means of a flexible member 52 extending along the discharge pipe 50 and adapted to be fastened by a pin or the like 53. (See Figures 1 and 8.)

I will now describe the operating mechanism of my snow handling machine.

On the shaft 54 of the engine 13 is loosely mounted a sprocket 55. On the shaft 40 within the channel 44 is a sprocket 56. (See Figures 1, 2, 3 and 7.) A chain 57 travels on the sprockets 55 and 56 for transmitting motion from the sprocket 55 to the shaft 40. I will later describe the clutch member for the sprocket 55.

Located above the shaft 40 is a transverse shaft 58 supported between the fan casings and having thereon sharp-edged discs 59. On the shafts 40 and 58 are sprockets 60 and 61. (Figure 4.) A chain 63^a travels on the sprockets 60 and 61 and transmits rotation from the shaft 40 to the shaft 58.

On one end of the shaft 40 is a worm 62 which meshes with a worm wheel 63 on a shaft 64 outside the walls 16 and extending forwardly to the shaft 20.

The shaft 64 is journaled in casings 65 and 66 on one of the walls 16. The worm wheel 63 is rotatably but non-slidably mounted on the shaft 64.

At the forward end of the shaft 64 is a worm 67 which meshes with a worm wheel 68 on the shaft 20 hereinbefore referred to, forming part of the rotary snow receiving device.

I will now describe the clutch structure, which is used at various points on my machine.

On the worm wheel 63 is formed a clutch member 69. Slidably mounted on the end of the shaft 64 adjacent to the clutch member 69 is a clutch member 70, which is actuated by a wire 71 sliding in a flexible casing 72. The flexible casing 72 and wire 71 are extended rearwardly and are supported at their rear ends by a plate 73, (see Figure 1), adapted to be mounted on the truck or tractor 74 from which the clutches may be actuated.

The clutch structure just described is illustrated in detail in Figure 6.

It will be understood that the clutch member 70 is splined to the shaft 64 and has the head or end 77 to which the wire 71 is fixed.

Receiving the end of the motor shaft 54 is a casing member 75 shown in Figure 1, in which is a clutch structure similar to that already described for connecting the shaft 54 and the sprocket 55 thereon.

The shafts 40 and 33 are connected by a shaft 64^a and by gearing mechanisms similar to those described as connecting the shafts 40 and 20, similar casings to the casings 65 and 66 already described being shown in Figure 1.

The clutch wire operating casings 72 leading to the clutches for throwing the sprocket 55 and the shaft 64^a in gear are shown in Figure 1, and are similar and used with similar clutches to that already described.

I have provided suitable mechanism for 75 tilting the side frame members 16 and the parts connected therewith on the shaft 15 for raising and lowering the forward end of the snow handling device, so that such end may be lowered while the machine is in operation 80 and raised while it is being transported from place to place without being in operation.

On the fan casing discharge pipes 49 are brackets 78 in which are slidably mounted rods or the like 79 having thereon collars 80. 85 The rods 79 extend downwardly and have formed on their lower ends rack bars 81.

Mounted on the rods 79 between the collars 80 and the brackets 78 are coil springs 82. The rack bars 81 slide in guides 83 on brackets 90 84 supported on the frame members 10. A transverse shaft 85 is supported on the brackets 84 and is provided with pinions 86 meshing with the respective rack bars 81.

On the end of the shaft 85 is a crank handle 87 for actuating the shaft 85.

For locking the shaft 85 in any adjusted position, I have provided the following means:

A locking pawl 88 (Figure 9) has an elongated slot 89. Pins 90 are extended from the brackets 84 through the slot 89 for supporting the pawl 88 for vertical sliding movement below one of the pinions 86. On the pawl 88 is a handle 91.

In the lower part of the pawl 88 is a socket 92 receiving one end of a coil spring 93, the lower end of which is seated as at 94 in the bracket 84 for yieldingly holding the pawl 88 in its upper position for locking the pinion 110 86.

When it is desired to manipulate the crank handle 87 for rotating the shaft 85 for tilting the walls 16 and the parts supported thereby, the operator grasps the handle 91 and lowers the pawl 88 to nonengaging position and then operates the crank 87.

For further controlling the feeding of snow, I have provided at the forward end of the machine at the sides thereof, arms 96 projecting upwardly and forwardly from the side wall members 16 and supporting at their upper ends substantially above the shaft 20 a transverse rod 97.

On the rod 97 are adjustably mounted a plurality of spaced collars 98 in which are adjustably mounted downwardly and rearwardly extending rods 99, which serve to

break up any large chunks of snow or to prevent the discharge to the endless conveyor of any chunks that are not so broken.

The arms 96 may be braced by braces 100.

5 Pivoted to the upper forward edge of the portion 43 of the conveyor casing 41 is a shield or the like 101 extending across the machine from side to side between the walls 16 as shown in Figures 1 and 2. At its forward edge, the shield 101 is connected with a transverse shaft or rod 102 extended through arcuate slots 103 in the walls 16.

Outside one wall 16, the shaft 102 has a head 104 shown in Figure 1 and outside the 15 other wall 16, there is secured onto the shaft 102 a nut 105, preferably of such size and shape as to be manipulated by hand, which can be tightened on the shaft 102 against the wall 16 for locking the forward edge of the 20 shield 101 in various adjusted positions.

It will be seen that the shield 101 limits the amount of snow permitted to be carried to the extreme upper end of the endless conveyor and discharged therefrom.

25 When the operator of the machine sees snow begin to pile up over the shield 101, he can readily determine that the truck or tractor should be driven more slowly until the conveyor arms or blades 45 and the blower 30 fans can handle the snow supplied thereto.

The position to be given the shield 101 must be determined by the experience of the operator with different kinds of snow.

I will now describe the means for connecting my snow handling machine with the 35 truck or tractor 74.

At the rear ends of the frame members 10 are upright brackets 106 having vertically spaced, rearwardly extending ears or lugs 40 107, in which are mounted upright angular rods 108. Bracket members 109 are mounted on the rods 108 for vertical sliding movement thereon and extend rearwardly and have at their rear ends socket members 110.

45 Fixed as on the frame of the tractor or truck 74 are brackets 111 having balls 112 at their forward ends received in the socket members 110.

The upper halves 113 of the socket members are bolted to the brackets 109 as by 50 bolts 114. On the rods 108 above the brackets 109 are heavy coil springs 115 and on said rods below the brackets 109 are lighter coil springs 116. The casings 72 for the clutch 55 operating wires may be gathered together 55 and held by a clip 117 on one of the frame members 111 as shown for instance in Figure 1.

I will now describe the practical operation 60 of my snow handling machine.

It will be understood that the machine is connected in the manner particularly illustrated in Figures 1 and 3 with a tractor or truck. The plate 73 is designed to be mounted 65 on the instrument board or at any point

suitable for the convenience of the truck or tractor operator.

I have not particularly described the means for actuating the clutch operating wires 71 at their rear ends because such structure is well known and in itself forms no part of my present invention.

70 It will be seen that the means for connecting the snow handling machine with the truck affords considerable flexibility.

75 The snow handling device may tilt with relation to the truck on account of the ball and socket structure shown in Figure 3.

When the machine is being propelled over the road, and is not operating, the forward 80 end thereof is tilted upwardly. This is accomplished by lowering the pawl 81, shown in Figure 9, and operating the crank handle 87, shown in Figure 1, for rotating the shaft 85 and the pinions 86 for pulling the rack 85 bars 81 (Figure 2) downwardly. This, of course, may compress the springs 115 (Figure 3) somewhat.

When the place of operation is reached, the tilting operation is reversed and the front 90 end of the snow handling mechanism is lowered.

In order to prevent the snow from getting under the rotary device hereinbefore described, the shoes 31 can be held against the 95 road with pressure by forcing the rack bars 81 upwardly until the springs 82 (Figure 2) are compressed for exerting tension upwardly on the rear part of the snow handling device, and thus pressing the forward part 100 downwardly over the fulcrum formed by the shaft 15.

On account of the construction hereinbefore shown and the castor wheels 14, it will 105 be seen that the snow handling mechanism will be steered according to the direction of the movement of the truck.

The operator manipulates the proper clutch operating wire 7 for throwing the 110 sprocket 55 into gear with the shaft 54 (see Figures 1 and 3) whereupon the shaft 54 will 115 rotate the sprocket 55 and thus impart motion to the chain 57, the sprocket 56 (see Figures 2 and 4), and the shaft 40. The operator then operates the proper clutches for actuating the shafts 64^a and 64 (Figures 1 and 5) for thus imparting motion from the shaft 40 to the shaft 33 (Figure 2) and to the shaft 20. The endless conveyor is thus put in movement, and the rotary device at the front of 120 the machine commences operation.

It is understood that the shaft 58 is actuated by the chain 63^a and sprocket mechanism shown in Figure 4.

125 As the machine is advanced along the road, the pockets formed by the pusher blades 24 and discs 21 fill with snow. As the pockets rotate upwardly and rearwardly past the vertical center of the rotary device, the pusher blades 24 are swung outwardly thus discharg-

ing the snow upon the endless conveyor. This movement is accomplished by the travel of the rollers 23 in the cam slots 19 in the fixed discs 17. (See Figures 2, 4 and 7.)

5 Any large chunks of snow are broken up by the rods 99 or simply rolled against the rods until they drop downwardly or are broken. The snow discharged upon the endless conveyor is slid upwardly and rearwardly on the bottom member 37 by means of the cross bars 38 and discharged into the conveyor casing 41. (See Figures 7 and 4.) The amount of snow fed over the discharge end of the endless conveyor is regulated by 15 the shield 101, which can be adjusted by loosening the nut 105 and raising or lowering the forward end of the shield 101 and then tightening the nut 105 for holding the shield 101 in the desired position.

20 As the snow is discharged from the endless conveyor, the discs 59 on the shaft 58 cut it into comparatively small particles. The snow is also divided into finer parts by the conveyor blades 45 on the shaft 40, which 25 convey it respectively to the right and left to the fan casings 46 where the fan blades 47 pick it up and carry it bodily or blow it to the discharge pipes 49 and 50. From the discharge pipes 50, the snow is blown to the 30 side of the road. By adjusting the hoods 51, the snow can be blown downwardly into a ridge at the sides of the cleaned path or may be blown away laterally.

The snow handling machine is a unit in 35 itself and can be readily stored during the summer months. By making the machine in a self-contained unit, the power plant which is used for advancing it is not made useless during the summer period.

40 It will be seen that even if the snow is deep, it can be handled without clogging the machine by advancing the machine slowly and gradually taking the snow as fast as the endless conveyor, the conveyor blades 45 and the 45 blowers will handle it. If the snow is on the ground to only a shallow depth, the machine can be advanced more rapidly.

The flexible connection between the snow 50 handling machine and the truck or tractor which drives it, permit the proper adjustment of the machine for working conditions.

The advantage of a machine of this kind for cleaning paved roads especially in rural districts is obvious.

55 It will be understood that the particular structure, I have shown here, so far as details are concerned, is illustrative and that many changes can be made in the details of the structure and arrangement of the machine, 60 and it is my intention to cover by my claims any modified forms of structure or use of mechanical equivalents, which may be reasonably included within the spirit of my invention and the scope of my claims.

I claim as my invention:

1. In a machine of the class described, a frame, discs mounted at one end of said frame, a transverse shaft mounted in said discs, discs fixed on said shaft adjacent to said first discs, shafts mounted in said second discs, said first discs having in their adjacent faces cam slots, rollers on said shafts mounted in the second described discs and arranged to travel in said cam slots, a plurality of snow pusher blades extending between the second discs pivoted adjacent to the peripheries of said second discs and curved from side edge to side edge in the arc of a circle having its center in said first shaft, said second discs having curved slots receiving the shafts mounted in the second discs, said blades being secured to said shafts whereby when said first shaft is rotated, said second discs will be rotated for causing said snow pusher blades to be alternately swung inwardly and outwardly to form pockets to receive snow and then to eject the snow therefrom, said blades being so arranged that when at the outer limit of their movement they form portions of a drum. 65

2. In a machine of the class described, a frame, discs mounted at one end of said frame, a transverse shaft mounted in said discs, discs fixed on said shaft adjacent to said first discs, shafts mounted in said second discs, said first discs having in their adjacent faces cam slots, rollers on said shafts mounted in the second described discs and arranged to travel in said cam slots, a plurality of snow pusher blades extending between the second discs pivoted adjacent to the peripheries of said second discs and curved from side edge to side edge in the arc of a circle having its center in said first shaft, said second discs having curved slots receiving the shafts mounted in the second discs, said blades being secured to said shafts whereby when said first shaft is rotated, said second discs will be rotated for causing said snow pusher blades to be alternately swung inwardly and outwardly to form pockets to receive snow and then to eject the snow therefrom, said blades being so arranged that when at the outer limit of their movement they form portions of a drum. 70

3. In a machine of the class described, a frame, discs mounted at one end of said frame, a transverse shaft mounted in said discs, discs fixed on said shaft adjacent to said first discs, shafts mounted in said second discs, said first discs having in their adjacent faces cam slots, rollers on said shafts mounted in the second described discs and arranged to travel in said cam slots, a plurality of snow pusher blades extending between the second discs pivoted adjacent to the peripheries of said second discs and curved from side edge to side edge in the arc of a circle having its center in said first shaft, said second discs having curved slots receiving the shafts mounted in the second discs, said blades being secured to said shafts whereby when said first shaft is rotated, said second discs will be rotated for causing said snow pusher blades to be alternately swung inwardly and outwardly to form pockets to receive snow and then to eject the snow therefrom, said blades being so arranged that when at the outer limit of their movement they form portions of a drum. 75

4. In a machine of the class described, a frame, discs mounted at one end of said frame, a transverse shaft mounted in said discs, discs fixed on said shaft adjacent to said first discs, shafts mounted in said second discs, said first discs having in their adjacent faces cam slots, rollers on said shafts mounted in the second described discs and arranged to travel in said cam slots, a plurality of snow pusher blades extending between the second discs pivoted adjacent to the peripheries of said second discs and curved from side edge to side edge in the arc of a circle having its center in said first shaft, said second discs having curved slots receiving the shafts mounted in the second discs, said blades being secured to said shafts whereby when said first shaft is rotated, said second discs will be rotated for causing said snow pusher blades to be alternately swung inwardly and outwardly to form pockets to receive snow and then to eject the snow therefrom, said blades being so arranged that when at the outer limit of their movement they form portions of a drum. 80

5. In a machine of the class described, a frame, discs mounted at one end of said frame, a transverse shaft mounted in said discs, discs fixed on said shaft adjacent to said first discs, shafts mounted in said second discs, said first discs having in their adjacent faces cam slots, rollers on said shafts mounted in the second described discs and arranged to travel in said cam slots, a plurality of snow pusher blades extending between the second discs pivoted adjacent to the peripheries of said second discs and curved from side edge to side edge in the arc of a circle having its center in said first shaft, said second discs having curved slots receiving the shafts mounted in the second discs, said blades being secured to said shafts whereby when said first shaft is rotated, said second discs will be rotated for causing said snow pusher blades to be alternately swung inwardly and outwardly to form pockets to receive snow and then to eject the snow therefrom, said blades being so arranged that when at the outer limit of their movement they form portions of a drum. 85

125

second discs pivoted adjacent to the peripheries of said second discs and curved from side edge to side edge in the arc of a circle having its center in said first shaft, said 5 second discs having curved slots receiving the shafts mounted in the second discs, said blades being secured to said shafts whereby when said first shaft is rotated, said second discs will be rotated for causing said snow 10 pusher blades to be alternately swung inwardly and outwardly to form pockets to receive snow and then to eject the snow therefrom, said blades being so arranged that when at the outer limit of their movement 15 they form portions of a drum, a cleaner arranged adjacent to the path of travel of the snow pusher blades and adapted to engage and clean them when they are at their outward limits of movement, a shield extending 20 from said cleaner to the bottom of said discs and provided with shoes.

4. In a machine of the class described, a frame, discs mounted at one end of said frame, a transverse shaft mounted in said 25 discs, discs fixed on said shaft adjacent to said first discs, shafts mounted in said second discs, said first discs having in their adjacent faces cam slots, rollers on said shafts mounted in the second described discs and arranged 30 to travel in said cam slots, a plurality of snow pusher blades extending between the second discs pivoted adjacent to the peripheries of said second discs and curved from side edge to side edge in the arc of a circle 35 having its center in said first shaft, said second discs having curved slots receiving the shafts mounted in the second discs, said blades being secured to said shafts whereby when said first shaft is rotated, said second discs will be rotated for causing said snow 40 pusher blades to be alternately swung inwardly and outwardly to form pockets to receive snow and then to eject the snow therefrom, said blades being so arranged that 45 when at the outer limit of their movement they form portions of a drum, a cleaner arranged adjacent to the path of travel of the snow pusher blades and adapted to engage and clean them when they are at their outward limits of movement, a shield extending 50 from said cleaner to the bottom of said discs and provided with shoes, there being four of said blades of such size that the four form four equal parts of a complete cylinder.

5. In a structure of the class described, a frame 74, a second frame secured at its rear end at laterally spaced points to said first frame or limited vertical sliding movement, having castor wheels under its front end, a 55 power plant on the second frame, a snow receiving and conveying mechanism mounted on the forward part of the second frame for pivotal adjustment with relation thereto, and

means for actuating the mechanism from the power plant. 65

6. In a device of the class described, a frame, a snow handling mechanism mounted thereon having spaced, aligned, transverse conveyor casings, a conveyor shaft extended between and into the casings, conveyor means 70 on the conveyor shaft in the respective casings, a disk shaft above said conveyor casings, disks on said disk shaft and operating gearing means connected with said shafts. 75

7. In a device of the class described, a frame, a snow handling mechanism mounted thereon having a conveyor casing, a conveyor shaft extended longitudinally through said casing, conveyor means on the conveyor shaft and in the casing, a disk shaft having 80 disks thereon mounted above said conveyor means, operating gearing means connected with the shafts means for conveying snow to said casing operated from said shaft, said snow first being discharged onto said disks. 85

8. In a structure of the class described, a frame 74, a second frame secured at its rear end to said first frame for limited, vertical, sliding movement and adapted to be moved horizontally by a movement of the first frame, 90 castor wheels under the front of the second frame, a power plant on the second frame, conveying means on the second frame, a fan casing communicating with said conveying means, a fan in said casing, a shaft for operating said conveying means and fan, means for actuating said shaft from the power plant including a clutch structure, a snow receiving and handling element, a conveyor for carrying snow from the said last element 95 to said first conveying means, means for actuating said element and said last-described conveyor from said shaft, including clutch devices. 100

9. In a structure of the class described, a frame 74, a second frame secured at its rear end to said first frame for limited, vertical, sliding movement and adapted to be moved horizontally by a movement of the first frame, 105 castor wheels under the front of the second frame, a power plant on the second frame, conveying means on the second frame, a fan casing communicating with said conveying means, a fan in said casing, a shaft for operating said conveying means and fan, means for actuating said shaft from the power plant including a clutch structure, a snow receiving and handling element, a conveyor for carrying snow from the said last element to said first conveying means, means for actuating 110 said element and said last-described conveyor from said shaft, including clutch devices, and flexible control members connected with said clutch devices and extended into said first frame. 115

10. In a structure of the class described, a frame 74, a second frame secured at its rear end to said first frame for limited, vertical, sliding movement and adapted to be moved horizontally by a movement of the first frame, 120 castor wheels under the front of the second frame, a power plant on the second frame, conveying means on the second frame, a fan casing communicating with said conveying means, a fan in said casing, a shaft for operating said conveying means and fan, means for actuating said shaft from the power plant including a clutch structure, a snow receiving and handling element, a conveyor for carrying snow from the said last element to said first conveying means, means for actuating said element and said last-described conveyor from said shaft, including clutch devices, and flexible control members connected with said clutch devices and extended into said first frame. 125
